UNITED STATES PATENT OFFICE.

JOHN REYNARD, OF OMAHA, NEBRASKA.

TRAFFIC-SIGNAL.

1,374,471.

Specification of Letters Patent. Patented Apr. 12, 1921.

Application filed July 25, 1919, Serial No. 313,338. Renewed February 21, 1921. Serial No. 446,863.

To all whom it may concern:

Be it known that I, JOHN REYNARD, a citizen of the United States, residing at Omaha, in the county of Douglas and State of Nebraska, have invented certain new and useful Improvements in Traffic-Signals, of which the following is a specification, reference being had therein to the accompanying drawing.

10 The invention relates to traffic signals and has for its object to provide a traffic signal of this character wherein an upright is pivotally mounted within a base whereby said upright may be pivoted in a horizontal plane as desired and to provide the upper end of said upright with a pair of horizontally disposed arms on which various signals may be printed. Also to provide means passing through the pivotal ends of the 20 arms and the standards whereby said arms will be maintained in horizontal positions and also means for maintaining and securing the arms in a vertical position so that the upright and stand may be easily moved 25 from place to place as desired.

With the above and other objects in view the invention resides in the combination and arrangement of parts as hereinafter set forth, shown in the drawings, described and 30 claimed, it being understood that changes in the precise embodiment of the invention may be made within the scope of what is claimed without departing from the spirit of the invention.

35 In the drawings:—

Figure 1 is a perspective view of the signal showing the arms extended.

Fig. 2 is a detail sectional view taken on line 2—2 of Fig. 1.

40 Fig. 3 is a detail sectional view similar to Fig. 2 but showing the arms extending downwardly and the squared portions of the locking bolt moved out of engagement with the square holes in the arms and in position 45 to swing into locking engagement.

Fig. 4 is a detail perspective view showing the squared apertures in the arms and standard.

50 Fig. 5 is a perspective view of the locking bolt.

Referring to the drawings, the numeral 1 designates a round base which is preferably made of cast iron and is provided with a socket 2 for the reception of the round 55 portion 3 of the standard 4. The lower end of the standard is provided with an annular

groove 5, which is adapted to receive the inner end of a screw 6, thereby providing means for preventing the lower end of the standard from coming out of the socket 2 of the base and at the same time providing means whereby the circular base 1 may be tilted on its peripheral edge, thereby allowing the signal as a whole to be rolled and stored as desired, particularly at night during the hours that it is not necessary to maintain traffic policemen at street intersections.

The upper portion 7 of the standard is flat and is provided with a square aperture 8, there being arms 9 which are also provided with apertures 10 which are square and are in registration with the square aperture 8 in the flattened portion 7 of the standard. A bolt 11 passes through the square apertures 8 and 10, and is provided with square portions 12 and reduced portions 13 and 14 which are round, said reduced round portions 13 and 14 are adapted to be moved into registration with the square apertures 10 when it is desired to lower and lock the arms in a vertical position for storage or moving the same from place to place. This lowering of the arms and locking in lowered position is accomplished by grasping the end 15 and pulling axially thereon, the end or round portion 14 having threaded thereon an adjusting nut 16 which will compress the spring 17 until the parts assume the position shown in Fig. 3. When in the position shown in Fig. 3 it will be seen that the arms 9 will be allowed to swing downwardly for the reason that they are allowed to do so as the square apertures 10 are in registration with the round reduced portions 13 and 14 of the bolt 11, however after the arms 9 have been allowed to swing downwardly the bolt then being released, spring 17 will again move the bolt 11 so that the squared portions 12 will engage the squared apertures 10 and 8 thereby locking the arms in their downward positions.

From the above it will be seen that a locking means is provided, wherein the signal arms will be maintained in horizontal position, thereby eliminating cumbersome and unsightly braces and at the same time said locking means will allow the arms to be locked in a vertical position. It will also be seen that it will be possible by moving and changing the angle of the arms to

lock said arms at various angles for signal purposes.

The invention having been set forth what is claimed as new and useful is:—

- 5 A traffic signal comprising a base, a standard, the lower end of which is rotatably mounted in the base and its upper end being provided with a horizontally disposed square opening, a pair of arms, each provided with a square opening near one end thereof and adapted to align with said square opening in the standard, a bolt slidably mounted in the square openings in the arms and standard, said bolt being provided
10 with relatively spaced squared portions for
15 normally locking the said standard and the arms, reduced cylindrical portions on said bolt adapted to be moved into registration with said squared openings in the arms when it is desired to change the position 20 of the arms and an enlarged hub integral with the bolt to limit its inward movement and terminating in a ring portion for permitting the bolt to be withdrawn to an inoperative position and a spring for holding 25 the bolt in a normally locked position.

In testimony whereof I hereunto affix my signature.

JOHN REYNARD.
